TRAILER SLED FOR A SNOWMOBILE

Merlin W. Ehrlichmann, 12475 W. Creek Road,
Minnetonka, Minn. 55343

Filed Oct. 16, 1967, Ser. No. 9,017

Term of patent 3½ years

(Cl. D14—24)

FIG. 1 is a side elevational view of a trailer sled for a snowmobile, showing my new design.

FIG. 2 is a front elevational view.

FIG. 3 is a rear elevational view.

FIG. 4 is a top plan view.

FIG. 5 is a bottom plan view thereof.

I claim:

The ornamental design for a trailer sled for a snowmobile, as shown.
